Primary Examiner — Dana Meyrow(74) *Attorney, Agent, or Firm* — Panitch Schwarze
Belisario & Nadel LLP**CLAIM**

The ornamental design for a jar, as shown and described.

DESCRIPTION

FIG. 1 is a top perspective view of a jar in accordance with my new design;

FIG. 2 is a front elevational view thereof, rear elevational and side elevational views being substantially the same;

FIG. 3 is a top plan view thereof; and

FIG. 4 is another top perspective view thereof of the jar of FIGS. 1–3 shown with an unclaimed cap; and,

FIG. 5 is an top perspective view thereof with a preferred cap mounted thereto.

The broken lines depict portions of the environment that form no part of the claimed design.
